(57) CLAIM

The ornamental design for a shoe bottom and periphery, as shown and described.

DESCRIPTION

FIG. 1 is a perspective view of a shoe bottom and periphery showing my new design;

FIG. 2 is a bottom plan view thereof;

FIG. 3 is a left side elevational view thereof;

FIG. 4 is a right side elevational view thereof;

FIG. 5 is a front elevational view thereof; and,

FIG. 6 is a rear elevational view.

The broken line showing the sole in the figures is for illustrative purposes only and forms no part of the claimed design.
